ATOMIZER

Richard H. Seaman and Albert Monk,
Los Angeles, Calif.

Application October 9, 1936, Serial No. 104,807

3 Claims. (Cl. 128—173)

Our invention relates to atomizers, and in particular to atomizers designed to spray medicinal liquids, and among the objects of my invention are:

5 First, to provide an atomizer which produces a particularly fine fog or mist and is particularly designed to atomize certain medicines for the treatment of asthma or kindred ailments for the reason that such medicine is usually powerful 10 and undue concentration or large drops thereof is apt to be detrimental.

Second, to provide an atomizer which is extremely compact in design and so arranged that it may be variously connected with a conventional 15 rubber bulb, either inserted substantially within the bulb with only its discharge end protruding, or arranged merely with its air intake end inserted in the bulb, or further, connected with the bulb through a tube.

20 Third, to provide an atomizer which incorporates a novel valve arrangement which insures against dripping of medicine from the air intake end of the atomizer and further, minimizes back flow of medicine into the air intake tube even 25 though the liquid is shaken in the atomizer.

Fourth, to provide an atomizer which operates efficiently on a small quantity of liquid and continues to so operate until only a negligible amount of liquid remains.

30 Fifth, to provide an atomizer wherein all moisture particles or drops which may issue from the atomizing element are caused to impinge on the walls of the discharge tube so that they may drain back leaving the truly atomized portion 35 of the liquid to be discharged.

Sixth, to provide an atomizer which incorporates at its discharge nozzle a novel baffle arrangement which insures against discharge of unatomized particles.

40 Seventh, to provide an atomizer wherein the parts may be readily assembled and disassembled and which is particularly simple and economical of manufacture.

With the foregoing and other objects in view 45 as may appear, hereinafter reference is directed to the accompanying drawing:

Figure 1 is an elevational view of our atomizer shown mounted in an atomizer bulb.

Fig. 2 is an enlarged longitudinal sectional view 50 of the atomizer without the bulb.

Fig. 3 is a transverse sectional view through 55 3—3 of Fig. 2.

Fig. 4 is another transverse sectional view through 4—4 of Fig. 2.

Fig. 5 is a perspective of the foot valve designed

to minimize dripping from the air intake of the atomizer.

Fig. 6 is a fragmentary longitudinal sectional view of a modified form of atomizer in which the atomizer element is removably mounted in the 5 atomizer shell.

Fig. 7 is a transverse sectional view through 7—7 of Fig. 6.

Fig. 8 is another transverse sectional view through 8—8 of Fig. 6.

Fig. 9 is a further transverse sectional view through 9—9 of Fig. 6.

The atomizer is enclosed in a tubular shell 1 which is substantially constant in diameter throughout and bent near one end to form two 15 angularly disposed arm portions forming a liquid chamber 2 and a nozzle 3. The lower end of the chamber 2 is substantially closed by an upwardly extending air tube 4 which tapers toward its extremity. The air tube is directed 20 in a curve so that its mid-portion is adjacent the side wall and its extremity or tip 5 is directed at an angle with and almost intersecting the longitudinal axis of the chamber.

A siphon tube 6 extends along the side of the 25 air tube and is substantially straight except for its discharge end 7 which turns toward the tip 5 of the air tube whereby a jet of air issuing from the air tube tends to draw liquid up the siphon tube in the usual manner of atomizer elements. 30 The siphon tube may be supported intermediate its ends from the air tube by a web 8.

Below the juncture of the air tube 4 with the 35 chamber 2 is a tapering stem 9 terminating in a slightly belled end 10. Fitted in the stem 9 is a foot valve 11 in the form of a socket constructed from flexible material such as rubber. One end of the foot valve is closed except for a diametrically extending slit 12 and a substantially right angularly disposed radial slit 13. The walls of 40 the foot valve are thin except for its open end which is thickened by a flange 14. The flange 14 fits the belled end 10 of the stem 9 while the remainder of the foot valve extends into the stem.

The tips 5 and 7 of the air and siphon tubes are preferably disposed at equal angles to the longitudinal axis of the chamber with the tip of the siphon tube slightly ahead of the other. This arrangement causes the spray from the 50 atomizer element thus formed to discharge in a cone 15 as indicated by arrows in Fig. 2. Approximately opposite the plane at which the cone strikes the walls of the chamber, the chamber is provided with an annular channel 16 which 55

forms an external rib 17. The particular location of the channel 16 tends to break up and further atomize the stream issuing from the atomizer element. Furthermore liquid particles or drops which still remain tend to consolidate on the walls of the shell and drain back. Should these be urged by the air stream in the shell to the nozzle 3, the extremity thereof is provided with a flange 18 which is directly both radially and axially inwardly and which forms a channel 19. Said channel prevents such liquid particles being discharged with the atomized or vapor stream.

Attention is now directed to Figs. 6 to 9 inclusive. Insofar as its operation is concerned, the structure here illustrated is similar to the first described structure, but provides certain advantages in the way of economical manufacture, and cleaning.

A shell 21 is provided, the nozzle end of which is identical to the first structure, so that only the chamber end 22 is shown. This portion is in the form of a straight tube. A body member 23 preferably formed of readily molded material such as a synthetic resin incorporates a plug portion 24 having an annular channel adapted to receive a gasket 25 of yieldable material. Below the plug 24 the body member 23 forms a stem 26 having a belled extremity 27 in which fits the foot valve 11 as in the first described structure, there being a cavity 28 above the belled end 27. Inwardly of the plug 24 the body member is provided with a support 29 having a bore 30 extending its length and intersecting the cavity 28. A second bore 31 is formed beside the bore 30, this intersecting a notch 31a in the side of the support 29. The bores 30 and 31 receive respectively an air tube 32 and a siphon tube 33. These tubes may be identical in construction and straight except for angularly disposed tips 34. By providing shoulders 35 and 36 insertion of the tubes in their respective bores may be so limited that they may be readily positioned in the correct relation with each other.

Each part employed in this arrangement is capable of being molded in quantity by automatic machinery and require little or no hand work other than assembly. Furthermore, although atomizers are inherently hard to clean the several parts of the above described structure are easily dissembled for cleaning. The arrangement of the air tube and siphon tube tips as well as the shell 21 thereabove being substantially identical to the first described structure, proper atomization of the medicine is assured.

With reference to the foot valve 11 used in

both structures, the particular arrangements of the valve slits therein tend to prevent sound producing vibrations. This is advantageous, for often, particularly when used by asthmatic sufferers, it must be operated in public. On the other hand, an occasional drop of medicine that may find its way down the air tube is prevented by the foot valve from passing out of the air intake end and into the conventional atomizer bulb 42 such as shown in Fig. 1 where it might contact and damage the metal check valve 41 therein.

Though we have shown and described particular embodiments of our invention we do not wish to be limited thereto, but desire to include in the scope of our invention the constructions, combinations and arrangements as set forth in the appended claims.

We claim:

1. An atomizer comprising; an atomizer chamber having an open end; a body member corking said open end and including a support extending into said shell, said support being notched at one side and having a pair of bores therein one intersecting said notch and the other extending through said body member; a pair of tubes fitting said bores and forming at their extended ends an atomizer unit.

2. An atomizer structure comprising: an elongated tube of substantially uniform diameter bent at its mid portion but otherwise straight; an atomizer unit in one end of said tube, and an inturned flange at the other extremity of said tube forming a trap for fluids traveling from the atomizer unit along the walls of the tube, said tube being otherwise free of obstruction between the atomizer unit and said flanged end.

3. An atomizer structure comprising; an atomizer chamber adapted to contain a liquid for atomization; a siphon tube and an air tube in said chamber and coacting to form an atomizer nozzle disposed above the normal liquid level in said chamber; a check valve disposed in close proximity to the discharge end of said air tube to define therewith a chamber of rudimentary dimensions, whereby the contents thereof is immediately expelled therefrom during initial flow from said air tube; an elongated delivery tube extending from said atomizer chamber, said delivery tube being of uniform diameter and bent intermediate its ends; and a reentrant nozzle at the extreme end of said delivery tube tending to entrap fluids passing along the walls of said delivery tube, said delivery tube being otherwise unobstructed.
